APPARATUS FOR THE RECORDING OF
ASYMMETRIC OR NORMAL SOUND
FILMS

Otto Kurt Kolb, Chiswick, London, and Albert Stanley Pratt, London, England, assignors to British Acoustic Films Limited, London, England, a British corporation

Application January 30, 1940, Serial No. 316,308
In Great Britain March 9, 1939

5 Claims. (Cl. 179—100.3)

This invention relates to sound recording apparatus and more particularly to apparatus arranged to record either asymmetric or normal sound records. The asymmetric sound records produced by our improved apparatus are of the kind in which, on opposite halves of the sound track zone, there are recorded separate sound tracks which are in mutual counterphase, but which are each individually formed by symmetrical wave traces, so that on each said lateral zone the record produced is a complete "double-hump" registration of the recorded wave train.

For the production of records of the asymmetric or push-pull type, it has been previously proposed to arrange two separate oscilloscopes each working in counterphase as regards the phonic current input, but acting in phase as regards a bias controlling current; each oscilloscope has, therefore, produced a complete "noiseless" record trace in known manner and the two oscilloscopes have been so disposed in relation to a single combining objective optical system that the two record pencils producing traces have been projected side by side upon the sound track on the recording film.

According to the present invention apparatus for producing a photographic sound record either of the asymmetric or of the normal varying width constant density type, includes a single oscilloscope, two masks each bearing one or more triangular apertures, and means for moving the said aperture masks in opposite directions in accordance with the intensity of the sound being recorded.

In conjunction with the single oscilloscope there are arranged two movable masks, each bearing a triangular or multiple triangular aperture. By "multiple triangular aperture" is meant an aperture comprising a number of similar triangular components side by side for producing multiple traces such as could be used for making multiple trace normal "double-hump" sound records. For the production of asymmetric sound records, however, it is preferred to employ only two apertures, one on each mask, the two masks being arranged to be moved parallel or substantially parallel to each other, but in opposite directions, by means of a suitable drive unit or units to which is applied a current, or potential varying in accordance with the mean amplitude, peak or envelope variations of a recorded wave train.

The two masks referred to may be connected by means of a suitable mechanical linkage so that the triangular apertures formed in them

are moved parallel to themselves and both masks. The two masks may be moved by means of a single drive unit to which the bias or control current, or potential varying in the manner set forth may be applied.

Light is projected through the apertures in the two movable masks from a suitable source, such as an exciter lamp, on to the mirror of the single oscilloscope and thence on to a fixed mask bearing a linear slit.

When asymmetric records are being produced images of the two triangular apertures are formed upon this slit by means of optical lenses which images with increasing sound amplitudes, are moved in opposite directions at right angles to said slit, but which, being reflected from the oscilloscope mirror, vibrate at phonic frequencies in unison across said slit.

As the apices of the two triangles lie in opposite directions, the two light pencils passing through the slit, where it is covered by the opposed triangular images, vary in length in such a manner that the corresponding collinear images formed upon the recording film sweep out symmetrical wave traces in exact counterphase, whilst the mean width of each individual sound track on the two lateral zones is dependent upon the position in which the corresponding primary mask is moved by the shift or bias controlling current or potential.

The two oppositely movable primary masks may be mounted in a suitable fixture together with their drive unit or units, and this fixture may be either made withdrawable, so that it may be replaced by one bearing a single movable mask having a triangular or multiple triangular aperture for the recording of normal films, or one of the two movable masks of a pair may itself be formed with an additional aperture or apertures so that the fixture, as a whole, may be moved into a second operative position in which the images of the aperture or apertures in one mask alone may be thrown upon the recording slit for the purpose of effecting recording of the normal kind instead of that of the asymmetric kind.

For a more complete explanation of the nature of the invention and for exemplifying forms of apparatus in which it may be embodied, reference will be made to the accompanying drawings in which

Fig. 1 illustrates in perspective a general schematic arrangement of recording apparatus;

Fig. 2 indicates in perspective a simple ar-

angement for moving the recording masks in opposed directions; and

5 Fig. 3 partly in side elevation and partly in vertical cross-section a preferred arrangement in which two recording masks are moved in opposed directions by a single moving coil drive unit, the whole arrangement being adapted to be shifted in relation to the recording light beam for the purpose of alternatively recording asymmetric or normal films.

10 In Fig. 1 light from a suitable source such as a lamp 1 is projected by means of an optical system 2 through apertures 3b and 4a, formed in masks 3 and 4, on to the mirror 5a of oscillo- 15 graph 5, so as to produce on secondary mask 6 images of the two apertures 3b and 4a. The mask 6 bears a transverse slit 6a and light passing through this slit is projected by means of objective system 7 on to sound track 8a of film 20 8. It will be seen that if the oscillograph 5 is stationary and the two masks 3 and 4 are moved in opposite directions, the two images 3b and 4a formed upon the mask 6 are moved over the slit 6a in opposite directions so that the average 25 breadth of the light strip relating to each image and passing through the lens system 7 is increased or diminished as the case may be. When, however, the oscillograph mirror 5a vibrates the light pencil representing one image is increased 30 whilst the other is diminished and vice versa, so that the associated sound traces are recorded in exact counterphase.

35 Referring to Fig. 1 it will be seen that the two masks 3 and 4 are mounted upon rods 9 and 10 which are linked by lever 11 and supported by parallel motion springs 12, 13 and 14. One of the rods, for example 9, is connected to a moving coil 15 which is disposed in the annular air gap 16a of a pot magnet 16.

40 The windings of moving coil 15 are traversed by a bias or controlling current produced in known manner, which varies in accordance with the mean intensity or peak amplitude or envelope variations of a sound to be recorded.

45 In Fig. 2 a similar arrangement of the two masks 3 and 4 is indicated, but in this case each of the rods 9 and 10 is connected to separate moving coils 15 and 15a and is supported by parallel motion spring systems 12, 14 and 12a, 50 14a respectively. In this case the bias currents passing through the two moving coil arrangements 15 and 15a are either reversed in phase or the magnetic field in which one of them is disposed is reversed in sense to that of the other 55 so that the two masks, with one direction of bias current flow, move in opposite directions.

60 In Fig. 3 an arrangement similar to that in Fig. 1 is shown partly in cross-section, the masks being mounted in a complete combined unit comprising the pot magnet 16 supporting frame 17 and the mechanical linkage constituted as before described. In this arrangement the two masks are driven in unison by the single coil 15. In this case, however, the magnet 16 is constructed 65 upon a base 18 which slides upon a fixed support 19. An indexing lever 20, has a termina-

tion 20a, formed as an index finger, which engages one or the other of the two notches 19a and 19b formed in the support 19. This arrangement serves to index or locate definitely in two alternative positions the mask system, so that either an image of the apertures 3b and 4a is formed upon mask 6 when asymmetric recording is in progress, or if mask 3 alone is brought into the recording light beam then an image of the apertures 3a, 3b is formed upon the said mask 6 so that a normal sound record of the twin double-hump "noiseless" variable area type is recorded. Alternatively, the arrangement could be such as to enable the aperture 4a alone to be brought into the recording light beam for producing a 15 normal sound record of the ordinary double-hump "noiseless" variable area type.

What is claimed is:

1. Apparatus for producing photographic sound records of the asymmetric and of the normal varying width constant density type, including a single oscillograph, two masks each bearing at least one triangular aperture, a source of recording light beam, means for selectively moving one or both masks with their apertures in the path 20 of the light beam to permit the production of sound records by employing one or both masks, and means for moving said masks in opposite directions with respect to one another in accordance with the intensity of the sound being recorded.

2. Apparatus according to claim 1, wherein electromagnetic means are provided for moving the aperture masks with respect to one another.

3. Apparatus according to claim 1, for producing an asymmetric sound record wherein the means for moving the masks in opposite directions comprise spring supported rods carrying the said masks, a lever through which said rods are linked, and a pot magnet having a moving 40 coil connected with one of said rods, said moving coil being energized in accordance with the intensity of the sound being recorded.

4. Apparatus for producing photographic sound records of the asymmetric and of the normal varying width constant density type, including a single oscillograph, two masks each bearing at least one triangular aperture, a source of recording light beam, means for selectively moving one or both masks with their apertures in the 45 path of the light beam to permit the production of sound records by employing one or both masks, means for moving the masks in opposite directions with respect to one another comprising spring supported rods carrying said masks, and a 50 moving coil within a pot magnet connected with each of said rods, said moving coils being energized in accordance with the intensity of the sound being recorded.

5. Apparatus according to claim 4, a base carrying the masks and the magnet, and the means for positioning the masks relatively to the light beam comprising a support upon which said base slides.

OTTO KURT KOLB,

ALBERT STANLEY PRATT.
